UNITED STATES PATENT OFFICE.

CHARLES G. SMITH, OF MEDFORD, MASSACHUSETTS, ASSIGNOR, BY MESNE ASSIGNMENTS, TO RAYTHEON MANUFACTURING COMPANY, OF CAMBRIDGE, MASSACHUSETTS, A CORPORATION OF MASSACHUSETTS.

ELECTRICAL APPARATUS.

Application filed May 3, 1921. Serial No. 466,517.

The present invention relates to electrical apparatus and more particularly to the type of apparatus disclosed generally in the co-pending applications of Smith, Serial No. 5 415,536, filed October 8, 1920, and Serial No. 418,263, filed October 20, 1920.

In this type of apparatus cooperating electrodes are immersed in a gas and so designed and arranged with respect to one another that all available paths for conduction through the gas are short and of the order of magnitude of the mean free path of the electrons and all paths through the insulating medium are sufficiently long to prevent breakdown of the medium. Such a construction may be employed as a rectifier of alternating currents by the introduction in the space between the electrodes of a magnetic field of suitable strength and direction. It is the object of the present invention to provide certain improvements in apparatus of this character tending to emphasize the characteristics which enable rectification to take place in addition to enlarging the permissible range of magnetic field. With this object in view it has been discovered that the cooperating electrodes may be so designed and located with respect to one another and to the lines of force of the magnetic field that there is a marked tendency to concentrate and localize the conduction in a well defined region.

In the accompanying drawings illustrating the preferred form of the invention Fig. 1 represents a sectional elevation of a tube embodying the principles of the invention; Fig. 2 is a section of the tube taken at right angles to Fig. 1; and Fig. 3 is a diagrammatic view illustrating a simple form of circuit in which the tube may be embodied as a rectifier.

The tube shown in the illustrated embodiment of the invention comprises the usual hermetically sealed receptacle 10 containing gas at the desired pressure. Received within the receptacle and immersed in the gas are cooperating electrodes 12 and 14 respectively. As will be observed from an inspection of the drawings, the cooperating electrodes are ring shaped, the outer electrode 14 having the form of a torus within which the inner electrode ring 12 is positioned concentrically, as will be self-evident. The outer electrode is conveniently formed

by two sheets 16 and 17 of aluminum which are pressed into the shape indicated clearly in Fig. 2, so that when joined the sheets cooperate to form the hollow circular tube 18. The sheets are respectively provided with fins 19 and 20. Lugs 21 project alternately from the fins 19 and 20 and are adapted to be bent over the cooperating fin to secure the sheets together. The outer electrode member 14 is provided with a tubular neck portion 24 which is rigidly connected at its lower end to a supporting arm 25 clamped to the base 26 of the receptacle by a ring 27 forming a part of the arm and held in place by encircling wires 28. In addition, the outer electrode may be steadied and supported by supporting members in the form of wires 40 and 42 which extend from projections 44 on the insulating base to a point above the connection with the arm 25. The inner electrode 12 may consist of a copper or aluminum rod of circular cross section bent into a ring form, as indicated in Fig. 1, and having a straight supporting portion 30 which is mounted at the end opposite the electrode in the upper end 32 of the insulator base 26, the construction above described serving to maintain the inner and outer electrode members in the desired positions with relation to one another. The inner electrode member 12 may be connected with a lead, indicated at 50, and the outer electrode is connected with a lead 52, which passes through the wall of the base 26 and is connected to the outside of the neck portion 24, as indicated clearly in Fig. 2.

A magnetic field having the lines of force substantially straight and extending transversely of the tube in a direction substantially normal to the plane of the electrodes may be conveniently introduced in the space separating the electrodes by a permanent magnet arranged as indicated more particularly in Fig. 2 with the opposite poles positioned in close proximity to the flattened sides of the tube, the magnet being indicated at 54. In the illustrated embodiment of the invention and with a magnetic field of the type described introduced between the electrodes the tube may be caused to freely conduct when the outer electrode is negative and acts as a cathode and to insulate against conduction when the inner electrode is negative and acts as the cathode. The discharge,

moreover, when the outer electrode acts as a cathode is strongly concentrated in the region of a plane which is normal to the direction of the lines of force.

5 The concentration of the discharge in this region is believed to be caused by the tendency of the magnetic field in conjunction with the curvature of the electrode surfaces to divert the paths of electrons which start 10 in a region removed from the plane toward the plane. Owing to this diversion of the paths of the electrons the new electrons are constantly liberated at points nearer the plane so that eventually the region of greatest 15 intensity of discharge is immediately adjacent to the plane. The advantage of a construction which functions in the above described manner is primarily due to the fact that it greatly enlarges the permissible 20 range of magnetic field over which rectification may take place.

The tube obviously may be embodied in a variety of circuits one of which is indicated in Fig. 3, this figure indicating a simple 25 form of circuit embodying the tube as a rectifier. As shown in the figure, an input circuit 60 is provided with a suitable source of alternating current 62, this input circuit being connected with the tube circuit 64 30 through a step-up transformer 66 to deliver alternating current of high potential to the tube indicated at 10.

I claim:

1. An electrical apparatus comprising a 35 hollow tubular electrode of circular shape, an inner electrode ring supported concentrically therewith, means for creating an electric field in the space between the electrodes, and means for introducing a magnetic field between the electrodes with the lines of force extending in a direction substantially normal to the plane of the electrodes.

2. An electrical apparatus comprising 40 toroidal electrodes supported in concentric

relation and immersed in a gas, means for creating a radial electric field in the space separating the electrodes, and means for introducing a magnetic field with the lines of force extending substantially normal to the 50 plane of the electrodes.

3. An electrical apparatus comprising a hollow circular electrode having a tubular neck portion, an electrode ring supported in the hollow electrode and having a stem, an insulator base connected with the stem to support the ring in concentric relation to the outer electrode, connections between the base and the tubular neck of the outer electrode, and leads connected respectively with the inner and outer electrodes. 55

4. An electric apparatus comprising a gas filled receptacle, a curved electrode immersed therein, a second curved tubular electrode surrounding the first electrode, with the longitudinal curved axis of the first electrode lying inside the cross-sectional outline of the tubular electrode, both electrodes lying substantially in a plane, and means for impressing a substantially straight magnetic 60 field across the electrodes in a direction perpendicular to said plane. 65

5. An electrical apparatus comprising a rod shaped electrode and a surrounding tubular electrode immersed in a gas and having opposing surfaces spaced apart a distance comparable to the mean free path of electrons in the gas, means for applying a potential difference between the electrodes, and means for impressing a magnetic field 70 in a direction substantially perpendicular to the axis of the electrodes. 75

6. An electrical apparatus comprising internal and external toroidal electrodes, means for impressing an electric field between the electrodes, and means for impressing a magnetic field normal to the plane of the electrodes. 80 85

CHARLES G. SMITH.
